UNITED STATES PATENT OFFICE.

EDWARD J. HORN, OF ROYAL OAK, MICHIGAN, ASSIGNOR TO DETROIT TORCH AND MANUFACTURING COMPANY, OF DETROIT, MICHIGAN, A CORPORATION OF MICHIGAN.

FIRE POT.

Application filed May 31, 1922. Serial No. 564,765.

To all whom it may concern:

Be it known that I, EDWARD J. HORN, a citizen of the United States, residing at Royal Oak, in the county of Oakland and State of Michigan, have invented certain new and useful Improvements in Fire Pots, of which the following is a specification.

This invention relates to fire pots or plumbers' furnaces; it has for its object a device of this kind in which the chimney or coil cup is arranged to permit the burner to be removed without disconnecting the coil cup from the grid nor disengaging the grid from the supporting posts.

Another feature described and claimed in this application is the detachable connection between the coil cup or chimney and the grid.

In the drawings:—

Fig. 1 is an elevation of a complete fire pot including the improvements.

Fig. 2 is a plan view of the chimney showing also the preheating tube and burner.

Fig. 3 is an elevation of the chimney.

Fig. 4 is a section on the line 4—4 of Fig. 3.

Fig. 5 is a sectional detail showing how the chimney detachably engages with the grid.

From Fig. 1 the usual parts which go to make up a fire pot can be discerned. *a* is the fuel oil container; *b* the shield supported upon the grid *c*. This grid is supported upon the posts *d*. A bail *e* can be used to lift the pot. A pump *f* furnishes the air pressure to eject the fuel oil. *g* designates the fuel oil pipe which has a union nut connection *h* with the valve casing *i*. This fuel oil pipe carries the preheating tube *x* and has a convolution above the burner jet opening (not shown). I prefer to employ a burner shell such as described and claimed in the application of Frederick L. Lindorf, No. 515,500; however, the preheating tube and the burner can have the familiar coil form which is in common use in fire pots.

These preheating tubes or coils often become stopped up and require removal to clean them. With the ordinary fire pot it is necessary to remove the grid from the posts and also the coil cup or chimney *j* from the grid in order to disengage the preheating tube from these parts.

Improvements, however, have been made on this construction by employing a hinged section in the grid and also by providing a loop in the grid so that the preheating tube passes over the grid and thru this loop. Hence the pipe can be lifted out of the grid without disconnecting the grid from the posts or the cup from the grid. However, in each of these forms the burner tube *y* has to be removed from the preheating tube through the side of the coil cup before this disassembly can be made. It is the object of the present invention to provide an assembly of the parts and an arrangement which will not only permit the removal of the preheating tube without disengaging the grid but will also permit the bodily removal of the burner tube with the preheating tube.

This is accomplished by providing a pair of gates or doors *k* in the side of the chimney *j*. I call this member a chimney for the reason that this term seems more applicable with the type of preheating tube that I preferably employ. Ordinarily this element is called a coil cup for the preheating tube is in the form of a coil. However, this term becomes a misnomer in this case where the preheating tube does not take the form of a coil.

The construction of the gates and doors will be obvious after an inspection of Fig. 3. The central portions of the gates have their rear edges rolled over to form knuckle eyes *m*. The main shell of the chimney has portions bent over to form knuckle eyes *n*. These carry the usual hinge pintles *o* to complete the hinges. A pivoted hasp *p* is used to engage the keeper *q* and lock the two doors together.

Now obviously when it is desirable to remove the burner units inside of the chimney, all that is necessary to do, is to open the doors and, after disconnecting the union nut *h*, the burner parts including the preheating tubes, can be removed through the sides of the chimney.

Ordinarily the coil cup or chimney is secured to the grid by threaded studs that are welded or riveted to the top of the chimney and which pass through perforations in the grid. Nuts run on the top of these studs to secure the coil cup removably to the grid.

However, this is not a quickly detachable connection as it is considerable trouble to remove the one from the other.

I provide a much better and quicker assembly by casting lugs or hooks *r* on the bottom of the grid. The chimney is made with three turned out ears *s* projecting from the top edge and each provided with a central boss *t*. Now, obviously, the chimney may be 10 assembled onto the bottom of the grid by mating one ear to the side of each lug on the bottom of the grid, then turning the chimney in rotation to bring the ears in between the lugs and the bottom of the grid. The 15 bossed portions *t* of the ears may then rest on the tops of the lugs and the chimney will not ordinarily come loose from the grid. Or for that matter the boss may be of such depth as to require a slight distortion or the 20 springing of the metal when the parts are turned into play.

What I claim is:

1. In a fire pot, the combination of an integral grid, a chimney secured thereto provided with means to permit the opening up of the side of the chimney, and a burner and preheating tube having a detachable support and which may be removed laterally through the side of the chimney when the same is 30 opened up.

2. In a fire pot, the combination of an integral grid, a chimney secured to the grid, and provided with a pair of gates or doors in the side, and a preheating tube and burner 35 detachably supported and which may be removed laterally through the side of the chimney when the gates or doors are open.

3. In a fire pot, the combination of an integral grid, a chimney secured to the grid and provided with a swinging section on the 40 side of the chimney which allows an opening to be had into the interior of the chimney, and a preheating tube and burner detachably supported and which may be removed laterally through the side of the chimney 45 when the pivoted section is opened.

4. In a fire pot, the combination of a grid, a chimney secured thereto provided with a pair of doors in its side, a hasp and keeper for keeping the same closed, and a preheating tube and burner detachably supported and which can be removed laterally as a unit through the doors when the same are open.

5. In a fire pot the combination of an integral supporting grid, a depending chimney secured to the grid, a preheating tube and burner detachably supported on the fire pot and extending into the chimney below the grid, the chimney being provided with a 60 door extending vertically below the grid for a distance sufficient to permit the removal of the preheating tube and burner laterally when detached from the fire pot.

6. In a fire pot, the combination of an integral supporting grid a preheating tube and burner detachably supported on the fire pot, and a depending chimney secured to the grid and provided with a door of sufficient area to permit the lateral removal of the 70 preheating tube and burner when detached from the fire pot.

In testimony whereof I affix my signature.
EDWARD J. HORN.
